CRUSHING AND GRINDING MILL

Frank Gross, Colorado Springs, Colo.

Application July 6, 1936, Serial No. 89,077

5 Claims. (Cl. 83—10)

My invention relates to ore crushing and grinding machines.

My object is to provide a machine of this class wherein a part intermittently rises and falls and at the same time has a continuous rotary motion, the function being to crush and grind ore. Other objects will appear as the description progresses.

Figure 1 represents a plan view of my machine; Fig. 2, a vertical cross section on the line 2—2 in Fig. 1; drawn to an enlarged scale; Fig. 3, a vertical cross section on the line 3—3 in Fig. 2; Fig. 4, a side view of the lower grinding member without the spiral grooves; Fig. 5, a top view of the lower grinding member with the spiral grooves; Fig. 6, a side view of the upper grinding member; and Fig. 7, a top view of the upper grinding member.

Although I show the preferred embodiment of my invention, I do not thereby limit myself to the precise form shown, but wish it understood that within the scope of what is hereinafter claimed, various changes in the details of construction may be made without departing from the spirit of the invention.

25 An annular plate 1, provided with an annular ball race 2, is mounted on legs 3. A vertically disposed shaft 4 is disposed concentrically with annular plate 1 and supported by struts 5 secured to legs 3. A series of balls 6 are disposed in ball race 2 in annular plate 1. A conical lower grinding member 7, provided with a bearing and a ball race, is mounted on shaft 4 so that the ball race is disposed on balls 6. A ring gear 8 is spaced from the lower grinding member 7, disposed concentrically therewith and secured thereto by radially disposed arms 9. A conical upper grinding member 10, provided with a collar 11, is mounted on shaft 4 so that said collar cooperates with shaft 4. Arms 12 extend from collar 11 to the main body of grinding member 10 so as to provide inlets 27 which communicate with the lower grinding member 7. The lower grinding member 7 and the upper grinding member 10 may be provided with spiral grooves 31 like those shown in Fig. 5 to facilitate grinding of the ore. Arms 15 extend radially from member 10, each arm being provided with a yoke 16. An internal ring gear 17 is spaced from ring gear 8 and secured to arms 15. A roller 18 is mounted in each yoke 16. 30 A curved top standard 19 is spaced from each leg 3 and connected thereto by a horizontal bar 20. The curved tops of standards 19 are disposed in the path of rollers 18. A vertically disposed shaft 21 is journaled in bearings 22—23. 35 A belt pulley 24 is mounted on shaft 21, and a

gear 25 is mounted on shaft 21 so as to engage the ring gears 8 and 7.

Crushed ore is led from the original crusher to the inlets 27 in the upper grinding member 10 as the grinding members 7 and 10 are rotating 5 on the shaft 4. When the rollers 18 meet the curved tops of the standards 19, the rollers are forced to ride over the tops and thereby lift the upper grinding member 10 so as to permit the crushed ore in the inlets 27 to flow downward 10 between the grinding members 7 and 10. When the rollers 18 have passed over the tops of the standards 19, the grinding member 10 drops down and crushes the ore and at the same time the rotary motion of the two grinding members 15 reduces the ore to finer particles. The intermittent vertical action combined with the rotary grinding action, facilitates the pulverizing of the ore.

The machine is actuated by a belt mounted on the pulley 24. The gear 25 being meshed with gears 8—7 and mounted on shaft 21, revolves gears 8—7 in opposite directions so that the grinding members are rotated in opposite directions.

I claim:

In a mill of the class described, the combination of a vertically disposed shaft; supports for said shaft; a lower grinding member mounted on said shaft; an upper grinding member provided with ore inlets and mounted on said shaft so as to cooperate with said lower grinding member; radially disposed arms mounted on said upper grinding member; a peripheral ring gear spaced from said lower grinding member and disposed concentrically with said shaft; arms connecting said ring gear with said lower grinding member; an internal ring gear spaced from said peripheral ring gear and secured to said radially disposed arms; a roller mounted on each radially disposed arm; a stationary cam disposed in the path of said rollers so as to cooperate with said rollers and radially disposed arms to lift said upper grinding member intermittently; a drive gear disposed between said ring gears and 40 meshed therewith; a shaft for said drive gear; and bearings for said last named shaft.

2. A mill of the class described comprising a vertically disposed rigidly mounted shaft; a lower grinding member, having a series of spiral 50 grooves in its grinding face, mounted on said shaft; an upper grinding member, having a series of spiral grooves in its grinding face and provided with ore inlets, mounted on said shaft so as to cooperate with said lower grinding mem- 55

ber; a peripheral ring gear spaced from said lower grinding member; bars connecting said peripheral ring gear to said lower grinding member; radially disposed arms mounted on said upper grinding member; an internal ring gear spaced from said peripheral ring gear and secured to said radially disposed arms; a roller mounted on each radially disposed arm; a series of stationary cams disposed in the path of said rollers so as to cooperate with said rollers and said radially disposed arms to lift said upper grinding member intermittently; bearings for a drive shaft; a vertically disposed drive shaft journalled in said bearings; and a drive gear mounted on 15 said drive shaft and meshed with said ring gears.

3. In a mill of the class described, the combination of a series of legs; an annular plate, provided with an annular ball race, mounted on said legs; a vertically disposed shaft located concentrically with said annular plate; supporting means for said shaft; a plurality of anti-friction balls disposed in said ball race; a conical lower grinding member, having an annular ball race, mounted on said shaft so that the ball race in 20 said grinding member cooperates with the anti-friction balls in the first named ball race; an upper grinding member, provided with inlets, mounted on said shaft so as to cooperate with said lower grinding member; a peripheral ring 25 gear spaced from said lower grinding member and disposed concentrically with said shaft; bars connecting said ring gear with said lower grinding member; radially disposed arms mounted on said upper grinding member; an internal ring gear 30 spaced from said peripheral ring gear and secured to said radially disposed arms; bearings mounted on one of said legs; a vertically disposed drive shaft journalled in said bearings; and a gear mounted on said drive shaft and meshed 35 with said ring gears.

4. In a mill of the class described the combination of a series of legs; an annular plate, provided with an annular ball race, mounted on said legs; a vertically disposed shaft located concentrically 40 with said annular plate; supports for said shaft; a plurality of anti-friction balls disposed in said ball race; a lower grinding member, having a

series of spiral grooves in its grinding face and provided with a ball race, mounted on said shaft so that its ball race cooperates with said anti-friction balls; an upper grinding member, having a series of spiral grooves in its grinding face and provided with inlets, mounted on said shaft so as to cooperate with said lower grinding member; a peripheral ring gear spaced from said lower grinding member and connected thereto; radially disposed arms mounted on said upper grinding member; an internal ring gear spaced from said peripheral ring gear and secured to said radially disposed arms; bearings mounted on one of said legs; a vertically disposed drive shaft journalled in said bearings; a gear mounted on said drive shaft and meshed with said ring gears; and a pulley mounted on said drive shaft.

5. In a machine of the class described the combination of a series of legs; an annular plate, provided with an annular ball race, mounted on said legs; a vertically disposed shaft located concentrically within said annular plate; supporting means for said shaft; a plurality of balls disposed in said race; a conical lower grinding member, provided with an annular ball race, mounted on said shaft so that the ball race in said grinding member cooperates with the balls in said first named ball race; an upper grinding member, provided with inlets, mounted on said shaft so as to cooperate with said lower grinding member; a peripheral ring gear spaced from said lower grinding member and disposed concentrically with said shaft; bars connecting said ring gear with said lower grinding member; radially disposed arms mounted on said upper grinding member; an internal ring gear spaced from said peripheral ring gear and secured to said radially disposed arms; a roller mounted on each radially disposed arm; a series of stationary cams disposed in the path of said rollers so as to cooperate with said rollers and radially disposed arms to lift said upper grinding member intermittently; bearings on one of said legs; a vertically disposed drive shaft journalled in said bearings; and a gear mounted on said drive shaft and meshed with 45 said ring gears.

FRANK GROSS.
